UNITED STATES PATENT OFFICE

LOUIS A. GEBHARD, OF WASHINGTON, DISTRICT OF COLUMBIA, ASSIGNOR TO WIRED RADIO, INC., OF NEW YORK, N. Y., A CORPORATION OF DELAWARE

RADIO TRANSMITTER

Application filed March 26, 1929. Serial No. 350,049.

My invention relates broadly to radio transmitters generally and more particularly to control circuits of thermionic tube transmitting systems.

5 One of the objects of my invention is to provide certain improvements in radio transmitters whereby the thermionic tubes are protected against a reversal of current in the control electrode biasing circuit.

10 Another object of my invention is to provide control circuits for radio transmitters whereby the energizing circuits are opened when the biasing potential supplied the control electrodes is not of the proper value.

15 Other and further objects reside in certain improvements in the circuit arrangements and control apparatus for radio transmitters, which will be more fully understood from the specification hereinafter following
20 and by reference to the accompanying drawings, wherein:

Figures 1 and 2 are schematic circuit diagrams showing different modifications of the improvements in radio transmitters of my
25 invention.

In thermionic tube transmitters operating at very high frequencies, and especially when high power water cooled tubes are employed as amplifiers, it is not unusual under operating conditions to have the biasing current in the control electrode circuit reverse its normal direction of flow. As is well known to those skilled in the art, thermionic tubes when employed as amplifiers of high frequency electrical energy must be operated at the proper portion of their characteristic curve. This portion of the curve is called the dynamic portion, being that portion where substantially like changes of plate current are caused by substantially corresponding changes of the potential supplied the control electrode. To maintain the normal control electrode potential at the proper value whereby the tube operates efficiently as a high frequency amplifier, it is usual to provide a potential for the control electrode whereby the control electrode is always maintained at a direct current bias potential of negative polarity with respect to the cathode.

50 Should such control electrode biasing poten-

tial be removed, the control electrode would be more positive with respect to the cathode. This increase of positive potential impressed upon the control electrode would cause an excessive increase of current in the anode circuit which would destroy, or at least damage, the thermionic tube. 55

The improvements in radio transmitters of my invention provide suitable protection for the thermionic tube, should such abnormal condition arise, as previously referred to. The current in the control electrode circuit may reverse its normal direction of flow. This causes an abnormal rise of anode current, and damage or possibly destruction of 65 the tube may result.

The improvements in radio transmitters of my invention provide suitable protection should this condition arise. It is well known to those skilled in the art that under certain 70 conditions the current in the control electrode circuit does reverse its normal direction in thermionic tubes operating at high frequency, and while the theory regarding such action is not definitely understood, the effect is nevertheless known to those skilled in the art. 75

Fig. 1 of the accompanying drawings shows one modification of the improvements in the radio transmitters of my invention. The circuit diagrams shown herein are schematic and are only for the purpose of explaining the arrangements and operation. Thermionic tube 1 is connected with an input circuit and an output circuit. The input circuit has a frequency stabilizing device whereby 80 the generated high frequency energy is substantially constant. The output of tube 1 is delivered to the input circuit of thermionic tube 2. The output of thermionic tube 2 is delivered to the input of tube 3. The output of tube 3 is delivered to the input circuit of tube 4 and the output circuit of tube 4 is delivered to load circuit 25. Load circuit 25 may be a space radio radiating system as shown, or physical circuits as employed in 85 wired radio systems. The cathode circuits are energized by source 26. The anode circuits are energized by sources 27 and 17. Control electrode biasing potential is supplied to thermionic tube 4 from source 10. 100

Source of energy 14 serves to supply the potential for energizing the several relay circuits.

The control electrode circuit for tube 4 is controlled in accordance with my invention since it is usually the high power tube which is subject to the abnormal condition heretofore mentioned. It is obvious, however, that like control means may be provided for the control electrode circuits of any number of tubes in the transmitter irrespective of their associated circuit and mode of operation. A relay 6 is provided, which is of polarized design, having windings 7 and 7a connected in series with the control electrode of thermionic tube 4, resistance 5, meter 28 and source 10. Meter 28 may be of the ampere or milliampere range and need not be included in the circuit unless desired. The current in the control electrode circuit is indicated by meter 28 and reversal of the normal direction is indicated to the operator by the meter vane. Should the direction of the current reverse, it is improbable that the attendant operator would close down the set in time to prevent damage to tube 4. The relay 6 is provided with an armature 6a, electromagnetically actuated thereby, carrying suitable contact members in positions adjacent to contact members 8 and 9. Armature 6a may be normally maintained in neutral position whereby contact members 8 and 9 are not contacting with armature 6a when the transmitter is not in operation. This opens the circuit from source 14 to momentary contact switch 11, whereby actuation of switch 11 will not energize relay 12. When source 10 is energized or the circuit supplying the control electrode biasing energy is completed, armature 6a is actuated.

The movement of armature 6a will not be sufficiently great, however, to close contacts 8 until the energizing potential from source 10 reaches a given value. When the potential from source 10 is of sufficient value armature 6a contacts with contact members 8, thereby completing the circuit to switch 11. Switch button 11a can now be closed thereby completing the circuit from source 14 to electromagnet 12. Electromagnet 12 actuates contacting armatures 15, 16. Contact members 15 are engaged whereby the energizing circuit to electromagnet 12 is completed when switch button 11a is released. Resistance 13 is connected in series with source 14 and electromagnet 12, and serves to limit the current through electromagnet 12. Contacting armature 16 is electromagnetically actuated by electromagnet 12 and electrically connected in series with source 17 and the anode circuit of thermionic tube 4. In Fig. 1, series feed anode supply through inductance 18 is shown, however, it is obvious that parallel supply circuits may be employed. Should the current in the control electrode circuit reverse

its normal direction of flow, armature 6a would not be attracted to contact member 8 and the energizing circuit of electromagnet 12 would be opened. This would cause contacting armature 16 to open thereby disconnecting the circuit from source 17 to the anode of thermionic tube 4. Observation of the current measuring device 28 would indicate that the current in the control electrode circuit had changed in that it had reversed its normal direction of flow.

Fig. 2 of the drawings shows another modification of the improvements in the radio transmitters of my invention. Reference characters employed in Fig. 2 correspond to those of Fig. 1. In Fig. 1, contact member 9 was not shown connected to any circuit; this contact member may however be connected with any suitable indicating lamp or the like. In the schematic circuit diagram shown in Fig. 2, contact member 9 is connected to one terminal of electromagnet 12 while armature 6a is connected to the remaining terminal. Switch 11 completes the energizing circuit to electromagnet 12 when switch button 11a is depressed. Contacts 15 are connected in parallel and complete the circuit when switch button 11a is released. Contacting armature 16 completes the anode energizing circuit from source 17. Should the current supplying the control electrode of thermionic tube 4 reverse its direction, armature 6a would be actuated and would swerve to the opposite direction, thereby contacting with member 9. This short circuits electromagnet 12 and causes the anode supply circuit from source 17 to be interrupted by the opening of contacting armature 16.

Many modifications of my invention are possible such as the number of tubes employed and sources of energizing potential, without departing from the spirit of my invention. It is to be clearly understood that the embodiments of my invention are not in any manner to be restricted by the accompanying drawings or by the foregoing specification but only by the scope of the appended claims.

What I claim as new and desire to secure by Letters Patent of the United States is as follows:

1. In a radio transmitter a thermionic tube, a source of control electrode biasing potential, a source of anode potential, a polarized relay having its winding connected in series with said source of biasing potential and the control electrode of said thermionic tube, said relay having a polarized armature and associated contacts connected to control the application of anode supply potential to said thermionic tube in accordance with the direction of current flowing in the winding of said relay.

2. In a radio transmitter, a thermionic tube, a source of anode potential, a source of control electrode biasing potential, a polar-

ized relay having its activating winding connected between said source of biasing potential and the control electrode of said tube, an electromagnetic circuit breaker having its contacts connected between said source of anode potential and the anode of said tube, the activating winding of said circuit breaker being connected to the contacts of said polarized relay through a source of potential, whereby the opening of the contacts of said relay opens the circuit of the activating winding of said circuit breaker.

3. In a radio transmitter, a thermionic tube, a source of anode potential, a source of control electrode biasing potential, a polarized relay having its activating winding connected between said source of biasing potential and the control electrode of said tube, an electromagnetic circuit breaker having its contacts connected between said source of anode potential and the anode of said tube, a source of potential connected to the activating winding of said circuit breaker, the contacts of said polarized relay being respectively connected to the terminals of the activating winding of said circuit breaker for short circuiting the activating winding of said circuit breaker when the contacts of said polarized relay are closed.
